EDWIN J. MCILVRIED, OF CLEVELAND, OHIO, ASSIGNOR TO THE VAUGHN MACHINERY COMPANY, OF CUYAHOGA FALLS, OHIO, A CORPORATION OF OHIO

MILL CONSTRUCTION

Application filed March 27, 1929. Serial No. 350,385.

The present invention relates to mills for use in the preparation of rubber stocks, and particularly to the improvement of the usual breaking cap incorporated in such mills.

It is the general practice in the construction of mills for this purpose to provide the adjustable journals or housings of one of the mill rolls with a frangible connection between the housing and the journal or box, so that if some foreign substance gets between the rolls, the connection will break and thereby injury to the expensive rolls will be avoided. This connection is usually in the form of a cap or disk mounted on the journal or box against which bears the adjusting screw, the disk being capable of fracture under excessive stress from the mill rolls.

In former constructions the replacement of a broken cap or disk has been an operation requiring considerable work and consequently has consumed valuable time both in making the repairs and in the loss of operating time on the mill. One of the objects of the present invention is to provide a new and improved arrangement for housing the breaking disk, whereby it is readily accessible and easily and quickly replaced.

In the present mill construction, if a workman's arm is caught in the mill rolls, it requires a considerable time to separate the rolls to free him. With the improved disk mounting shown and described herein, the mill rolls may be separated without delay by operation of the adjusting screw. In the mill roll constructions prior to the present construction the only way in which the mill rolls can be separated is by wedging them apart, this operation consuming much time in an emergency.

These and other objects will be apparent from a consideration of the detailed construction of the new form of mill roll, it being understood that the invention is not necessarily limited to a copying of the details of the invention, but may be embodied in other and modified forms within the scope of the invention as set forth in the claims. It will also be understood that the invention may be embodied in similar locations and for machines similar to the rubber mill, although its imme-

diate application, as will be described herein, is directed to that art.

In the drawing,

Figure 1 is a fragmentary view of one side of a rubber mill showing the invention incorporated therein, it being understood that the mill construction is of the usual or standard form and is not further illustrated for that reason;

Figure 2 is an enlarged sectional view 60 through the breaking disk mounting, being taken on the line 2—2 of Figure 3;

Figure 3 is a section on the line 3—3 of Figure 2; and

Figure 4 is a section on the line 4—4 of Figure 3.

In the drawing, 1 represents the mill housing, and 2 and 3 the two mill rolls, the former being the stationary roll and the latter the adjustable or movable roll. The stationary roll 70 is mounted in fixed bearing boxes 5 secured to the mill roll housing. The roll 3 is mounted in sliding boxes or journals 6 movable in ways 7 in the housing.

The mill rolls are held at the required distance apart by means of adjusting screws 8 which are mounted in the housing and bear upon the sliding journal 6 through the medium of the breaking cap to be described. The inner end of the screw 8 is provided with an 80 enlarged head or flange 10.

The breaking disk or cap is illustrated at 12, being located in a seat 14 formed on the front or forward face of a breaking disk housing 15, and covering a central opening 16 which 85 is of sufficient diameter to receive the end of the screw 8 in event of breaking of the disk. The adjacent side of the housing may be provided with a recess 18 registering with the opening 16. The breaking disk is retained 90 in the seat 14 by a plate 20 fitting within the seat and having an opening surrounding the screw and having a slot 22 opening therein to provide a groove adapted to receive a removable shoe 24. The inner end of the shoe is 95 forked as shown at 25 to pass on either side of the screw and over the flange 10. The outer end of the shoe is provided with an opening 26 by which the shoe may be removed. The plate 20 is secured to the break- 100

ing disk housing by screws 27 which enter the housing 15 and hold the breaking disk firmly across the opening in the housing so that its edges are clamped, and a clean breaking or shearing action is assured. The breaking disk is then held like a drum head and will shear positively, not bending or dishing as would be the case were the edges of the disk unconfined. The complete assembly is secured to the box 6 by screws 28 which pass through both 20 and 15 and enter the housing.

In the event of breakage of the disk 12 by shearing of the disk by the adjusting screw, the shoe 24 is removed and the adjusting screw 8 run back to such position that, after the screws 28 are removed, the entire breaking disk assembly, including the parts 15 and 20, may be removed from the adjustable housing 20 and the disk is replaced. If it is desired to separate the rolls in an emergency, such as may occur if a man is caught between the rolls, the adjusting screw is run back without first removing the shoe. As the shoe is over the flange 10, the whole of the adjustable housing is moved outwardly thereby separating the rolls quickly and easily.

The advantages of the invention are readily apparent to those familiar with this art, and it will be evident that one skilled in the art may embody the invention in other forms and modifications without departing from the essential features of the invention as set forth in the claims hereto appended.

25 3. What is claimed is:—

1. In a mill having a roll, a movable bearing for said roll, a screw limiting the outward movement of said bearing, a removable housing secured to the bearing, a seat on the housing, a breaking disk in the seat against which the screw bears, and a removable plate secured to the housing confining the rim of said disk in the seat, the dimensions of said screw and said housing being such that a breaking stress applied to the disk will be confined to shearing.

2. In a mill having a roll, a movable bearing for said roll, a screw limiting the outward movement of said bearing, a breaking disk assembly removably attached to said bearing, said assembly comprising a housing having a seat, a breaking disk in the seat and a plate over the breaking disk and attached to the housing, said plate having a central aperture through which the screw passes, and means to secure said assembly removably on the bearing, said housing and said screw being of such dimensions that a breaking stress applied to the disk will be confined to shearing.

3. In a mill having a roll, a movable bearing for said roll, a screw limiting the outward movement of said bearing, a breaking disk assembly removably attached to said bearing, said assembly comprising a housing having a

seat, a breaking disk in the seat and a plate over the breaking disk bearing on the rim thereof, and means to secure said assembly removably on the bearing, said screw, housing and plate cooperating with said disk whereby a breaking stress applied to the disk will be confined to shearing. 70

4. In a mill having a roll, a movable bearing for said roll, a screw limiting the outward movement of said bearing, a breaking disk assembly removably attached to said bearing, said assembly comprising a housing having a seat, a breaking disk on the seat and a plate over the breaking disk, and means to secure said assembly removably on the bearing, said assembly having a passage therethrough and the inner end of the adjusting screw being in register with and movable through said passageway, said screw, plate and housing cooperating with said disk whereby a breaking stress applied to said disk will be confined to shearing. 75

5. A mill having a roll, a movable bearing for said roll, a screw for limiting the outward movement of said bearing, a breaking disk assembly attached to said bearing, said assembly comprising a housing having a seat, a breaking disk in the seat, said screw bearing against the disk and a plate to secure the disk in its seat, an enlarged portion on the end of the screw, said enlarged portion and said housing cooperating with said disk whereby a breaking stress applied to the disk will be confined to shearing, and a removable shoe fitting over the screw forwardly of the enlarged portion thereof for actuating the bearing outwardly whether the disk is broken or not. 80

6. A mill for the purposes specified comprising a mill housing, opposed rolls in said housing, an adjustable bearing for one of said rolls, a screw in said housing, and a breaking disk assembly carried by the bearing, said assembly comprising a breaking disk housing having a seat, a breaking disk in the seat, a plate over the disk in its seat and a removable shoe in the plate, said shoe engaging a portion of the screw, the end of the screw bearing against the breaking disk. 105

7. A mill for the purposes specified comprising a mill housing, opposed rolls in said housing, an adjustable bearing for one of said rolls, a screw in said housing, and a breaking disk assembly removably mounted on the bearing, said assembly comprising a breaking disk housing having a seat, a breaking disk in the seat, a plate over the disk in its seat and a removable shoe in the plate, said shoe engaging a portion of the screw, the end of the screw bearing against the breaking disk. 110

8. A mill for the purposes specified comprising a mill housing, opposed rolls in said housing, an adjustable bearing for one of said rolls, a screw in said housing, and a break- 115

ing disk assembly carried by the bearing, said assembly comprising a breaking disk housing having a seat, a breaking disk in the seat, a plate removably secured in the housing over the disk in its seat and a removable shoe in the plate, said shoe engaging a portion of the screw, the end of the screw bearing against the breaking disk.

9. A mill for the purposes specified including a roll, an adjustable bearing for said roll, a screw for adjusting the bearing, and a breaking disk assembly attached to the bearing, said assembly comprising a housing and a plate removably secured together and having a passageway from the end of the screw, and a breaking disk located between the housing and the plate and spanning the passageway, said screw and said plate being of such dimensions that a breaking stress applied to the disk is confined to shearing.
